UNITED STATES PATENT OFFICE.

JOHN P. ARNETT AND JAMES T. FAIRCHILD, OF SALYERSVILLE, KENTUCKY.

CLUB.

1,240,005.

Specification of Letters Patent. Patented Sept. 11, 1917.

Application filed May 3, 1917. Serial No. 166,200.

To all whom it may concern:

Be it known that we, JOHN P. ARNETT and JAMES T. FAIRCHILD, citizens of the United States, residing at Salyersville, in 5 the county of Magoffin, State of Kentucky, have invented a new and useful Club; and we do hereby declare the following to be a full, clear, and exact description of the invention, such as will enable others skilled in 10 the art to which it appertains to make and use the same.

The present invention relates to certain new and useful improvements in clubs such as are commonly employed by policemen 15 and other officers of the law for use in overcoming any resistance which might be offered to the making of an arrest or other proper exercise of their authority, the object of the invention being to provide a club of 20 this character which embodies novel features of construction whereby it can not be snatched or forcibly pulled from the hand of the officer.

Further objects of the invention are to 25 provide a club of this character which is comparatively simple and inexpensive in its construction, which can be used in the same manner as an ordinary club, which is constructed so that sharp points will automatically be projected from the sides of the club should any attempt be made to grasp the club and pull it from the hand of the officer, and which is so constructed that it can be 30 easily assembled and taken apart.

With these and other objects in view, the invention consists in certain novel combinations and arrangements of the parts as will more fully appear as the description proceeds, the novel features thereof being 35 pointed out in the appended claims.

For a full understanding of the invention, reference is to be had to the following description and accompanying drawing, in which:

40 Figure 1 is a longitudinal sectional view through a club constructed in accordance with the invention, the pins being shown in a retracted position.

Fig. 2 is a side elevation of the club with 45 the pins in a projected position, portions being broken away and shown in section to illustrate more clearly the details of construction.

Fig. 3 is a transverse sectional view on the 50 line 3—3 of Fig. 1.

Fig. 4 is a similar view on the line 4—4 of Fig. 1.

Fig. 5 is also a similar view on the line 5—5 of Fig. 1.

Fig. 6 is an end view of the club with the 60 cap removed.

Corresponding and like parts are referred to in the following description and indicated in all the views of the drawings by the same reference characters.

65

Specifically describing the present embodiment of the invention, the numeral 1 designates the handle, and 2 the stock of the club which is carried by the handle, but which has a limited sliding movement 70 toward and away therefrom. The stock 2 is divided longitudinally into two interchangeable and complementary sections or halves 2^a which are adapted to be assembled from opposite sides, one side of each of the 75 halves being provided with a series of small positioning pins 3 which are adapted to engage corresponding openings 4 in the other half to bring the two halves or sections accurately together when they are assembled. 80 The outer end of the stock 2 is formed with a threaded stud 5, half of which is carried by each of the sections 2^a, said threaded stud being engaged by a cap 6 which assists in holding the stock sections 2^a together and 85 provides a suitable tip for the club. A sleeve 7 is fitted upon the inner end of the stock 2^a, being held removably in position by a suitable fastening member 8, and projecting beyond the end of the stock so as to telescope over the end of the handle 1. 90

The interior of the stock 2 is formed with a longitudinal bore or recess 9 within which a pair of opposed pin carrying bars 10 are mounted for in and out movement toward 95 and away from each other. Each of these bars 10 is provided with a series of pins 11 which project outwardly therefrom and are loosely received within radial openings in the side walls of the stock 2, said openings 100 being conveniently formed by corresponding notches or grooves 12 in the meeting faces of the sections 2^a of the stock. The points of the pins are normally retracted and sheathed within the radial openings of the 105 stock so that they are inoperative and do not interfere with the use of the club in the customary manner.

A rod 13 which has one end thereof 110 screwed or otherwise rigidly anchored in

- the handle 1, as indicated at 14, extends axially through the stock 2 and is arranged between the two pin carrying bars 10. A pair of V-shaped spring strips 15 are secured at their apexes to the rod 13, the ends of the strips being rigidly fastened to the respective pin carrying bars 10. The inherent resiliency of these V-shaped spring strips 15 normally tends both to draw the pin carrying bars inwardly and to hold the stock 2 against the handle 1. However, should the stock 2 be forcibly pulled away from the handle 1, the arms of the V-shaped springs 15 will be flexed apart, and the pin carrying bars forced outwardly, thereby causing the points of the pins 11 to be projected beyond the sides of the stock 2. The toggle action of the V-shaped springs 15 is due to the relative movement between the rod 13 and pin carrying bars 10, the latter being movable with the stock 2, while the rod is fixed to the handle 1. The automatic projection of the points of the pin 11 when the stock 2 is forcibly pulled away from the handle 1, would cause any person who might have grasped the stock 2 to quickly release the same, and any effort to snatch the club from the hand of the officer would thus be frustrated.
- 30 The inner end of the stock 2 is shown as provided with a pair of guide plungers 16 which are arranged upon opposite sides of the rod 13 and have a parallel relation thereto, said guide plungers being slidably received within corresponding openings 17 in the handle 1. These plungers 16 may be constructed with heads 16^a and have the ends thereof fitted within corresponding recesses 18 in the meeting faces of the stock sections 2^a. The various parts of the club are ordinarily held securely in operative position, although it will be obvious that by unscrewing the cap 6 and removing the sleeve 7 the two complemental sections 2^a of the stock can be separated and the club taken apart. The club has the same general appearance as the ordinary club and is intended to be used in the same manner as the ordinary club, with the pins 11 held in an inoperative position unless an attempt is made to forcibly pull the club from the hands of the officer, in which event the pins will be automatically projected into operative position so as to cause the quick release of the club by any hand which may have grasped the outer end thereof.
- Having thus described the invention, what we claim as new and desire to secure by Letters Patent, is:—
- 60 1. A club including a handle, a rod projecting from the handle, a stock slidably upon the rod, a pin carrying bar arranged within the stock parallel to the rod, normally retracted pins upon the bar, and a toggle connection between the bar and the rod for

automatically projecting the pins into operative position when the stock is moved upon the rod.

2. A club including a handle, a rod projecting from the handle, a stock slidably upon the rod, a pair of pin carrying bars arranged within the stock on opposite sides of the rod, normally retracted pins carried by the pin carrying bars, and V-shaped spring strips connected to the rod and respective bars, said spring strips serving to normally hold the stock in position against the handle, and having a toggle action for forcing the bars outwardly to automatically project the pins into operative position when the stock is pulled away from the handle.

3. A club including a handle, a rod projecting from the handle, a stock slidably upon the rod, guide means carried by the stock for engaging the handle, a pin carrying bar extending through the stock on one side of the rod, normally retracted pins carried by the pin carrying bar, and spring strips connecting the rod and pin carrying bar, said spring strips normally holding the stock against the handle and having a toggle action for forcing the pin carrying bar outwardly to automatically project the pins into operative position when the stock is pulled away from the handle.

4. A club including a handle, a rod projecting from the handle, a stock slidably mounted upon the rod and divided longitudinally into interchangeable complemental sections adapted to be assembled from opposite sides, said stock being formed with a longitudinal bore, a cap applied to the outer end of the stock to hold the sections together, a sleeve applied to the inner end of the stock and telescoping upon the handle, a pin carrying bar arranged within the bore of the stock on one side of the rod, normally retracted pins carried by the bar, and a toggle connection between the rod and the bar for forcing the bar outwardly and automatically projecting the pins into operative position when the stock is pulled away from the handle.

5. A club including a handle, a rod projecting from the handle, a stock slidably mounted upon the club and divided longitudinally into interchangeable complemental sections, said stock being formed with a longitudinal bore and the meeting faces of the complemental sections being correspondingly notched to provide radial openings leading from the longitudinal bore to the outside of the stock, a cap applied to the outer end of the stock for holding the sections together, a sleeve applied to the inner end of the stock and telescoping upon the handle, pin carrying bars arranged within the bore of the stock on opposite sides of the rod, normally retracted pins projecting from the bars and received within the before

mentioned radial openings, and V-shaped springs connected to the rod and bars, said springs normally holding the stock against the handle and having a toggle action for automatically moving the pin carrying bars outwardly to project the pins into operative position when the stock is pulled away from the handle.

In testimony whereof we have signed our names to this specification in the presence of 10 two subscribing witnesses.
